UNITED STATES PATENT OFFICE

JOHN A. MACREADY AND HARRY H. HODGSON, OF DAYTON, OHIO, ASSIGNEES TO
FRIGIDAIRE CORPORATION, OF DAYTON, OHIO, A CORPORATION OF DELAWARE

REFRIGERATING APPARATUS

Application filed June 30, 1928. Serial No. 339,422.

This invention relates to refrigerating apparatus and more particularly to a water cooling apparatus.

An object of this invention is to provide a water cooler having a food or bottled beverage storage compartment as well as a water cooling compartment.

Another object of this invention is to provide a water cooler provided with a water compartment and a food or bottled beverage storage compartment and in which a cylindrical float valve controlled evaporator may be placed so that it refrigerates properly both compartments separately.

20 Further objects and advantages of the present invention will be apparent from the following description, reference being had to the accompanying drawings, wherein a preferred form of the invention is clearly shown.

25 In order to cool the water and the food or bottled beverage, a cooling unit 32 may be provided which has thermal contact with the water compartment and with the food or bottled beverage compartment. As a

In the drawings:

Fig. 1 is a view partly in elevation and partly in section taken from the front of a water cooler embodying features of our invention:

21 and 22 may be provided with a common dividing wall 33 and the cooling unit 32 may be supported in contact with the dividing wall 33. As a further specific embodiment,

Fig. 2 is a view similar to Fig. 1 taken substantially at right angles to Fig. 1;

35 Fig. 3 is a view somewhat similar to Fig. 2 showing a modified form; Fig. 4 is a view of a portion of an apparatus shown in Fig. 3 in which a further

Fig. 5 is a diagrammatic view of a refrigerating system adapted to be used with a water cooler embodying features of our invention, and

Fig. 6 is a view in elevation partly broken away and showing a float valve controlled evaporator embodying features of the invention.

A water cooler embodying features of our invention may comprise a cabinet, generally designated as 20, which may be provided with a water cooling compartment, generally designated as 21, and a food or bottled

partment 21 is cooled through the medium of the thermal contact of the cooling unit 32 with the wall 34 and that the compartment 22 is cooled by the direct contact of the cooling unit 32 with the air in the compartment 22. A suitable door 41 may be hinged to the cabinet 20 in order to permit access to the compartment 22. A suitable door jamb 42 may be provided to receive the door 41.

Any suitable refrigerant liquefying unit may be provided and it may be located in any convenient place. If desired, it may be located in the lower half of the cabinet 5 in the compartment formed by the lower part of the panels of the cabinet.

As shown in Fig. 5 somewhat diagrammatically, the refrigerant liquefying unit may comprise a compressor 50 which delivers compressed refrigerant through the pipe 51 to a condenser 52. The refrigerant condensed in the condenser 52 is delivered through the pipe 53 to a liquid refrigerant receiver 54. A pipe 36 extending below the normal level in the receiver 54 delivers liquid refrigerant to the cooling unit 32 where the refrigerant is evaporated. The evaporated refrigerant leaves the evaporator 32 through the fitting 37 and returns to the compressor through the pipe 38 where the refrigerant is compressed to repeat the cycle. In order to render the operation of the unit automatic, an automatic switch may be provided for starting and stopping the motor 55 which drives the compressor 50. For instance, a pipe 56 may be connected to the low pressure pipe 38 and may be also connected to an expansible bellows 57 which operates the snap switch 58 for starting and stopping the motor 55.

If desired, the food or beverage compartment may be placed above the water compartment. For instance, as shown in Fig. 3, the cabinet 20a is provided at the top with a food or beverage compartment 22a under which there is placed the water compartment 21a. In this particular embodiment, the water may be supplied to the compartment 21a from the regular water supply pipes. Thus, a water inlet pipe 60 may be provided for delivering water to the compartment 21a. A suitable bubbling cup 61 may also be connected to the compartment 21a and the discharge of water may be regulated by a suitable valve 62. A drain pipe 63 may be connected to the drain pipe of the building in which the water cooler is located and this pipe 63 receives the waste water from the bubbling cup 61. A suitable door 41a may be provided in the cabinet 20a.

The opening for access into the food or beverage compartment may be placed at the side of the cabinet as shown in Figs. 1, 2, and 3, or, if desired, it may be placed on top of the cabinet. As shown in Fig. 4 the

top of the cabinet may be provided with a circular opening 65 and a lid 66 may be used for closing the opening. This lid 66, if desired, may be of the same type as is generally used for closing the ice cream containers in ice cream cabinets now in use.

It is thus seen that we have provided a water cooler which has a water cooling compartment and a food or bottled beverage compartment in which food or bottled beverages may be placed and in which an evaporator is located in thermal contact with both of said compartments in such a manner as to insure the proper temperatures in both compartments. By using a cylindrical boiler with a removable plate 35, standard equipment may be used. The boiler 32 is somewhat similar to the standard evaporators now in use and is adapted to use a standard float valve control plate 35 of the character now generally in use. The other parts of the cabinet are adapted also to receive standards parts now in use for domestic mechanical refrigeration.

While the form of embodiment of the invention as herein disclosed constitutes a preferred form, it is to be understood that other forms might be adopted, all coming within the scope of the claims which follow.

What is claimed is as follows:

1. A water cooler comprising a water cooling compartment, a food storage compartment in alignment with said water cooling compartment and having a common dividing wall, an evaporator in one of said compartments in contact with said wall.

2. A water cooler comprising a water cooling compartment, a food storage compartment in alignment with said water cooling compartment and having a common dividing wall, said wall being provided with a semi-cylindrical offset, and a cylindrical, float valve controlled evaporator in said offset.

3. A water cooler comprising an upright elongated cabinet, a water cooling compartment and a food storage compartment in said cabinet, in vertical alignment and of substantially the same horizontal dimensions, insulation on said compartments, a common dividing heat conducting wall between said compartments, draft means on said water cooling compartment, and an evaporator in one of said compartments in contact with said wall.

4. A water cooler comprising an upright elongated cabinet, a water cooling compartment and a food storage compartment in said cabinet in vertical alignment and of substantially the same horizontal dimensions, insulation on said compartments, a common dividing heat conducting wall between said compartments, draft means on said water cooling compartment, an evaporator in one of said compartments in contact

with said wall, means above said water cooling compartment for supporting an inverted demijohn with its neck in said water cooling compartment.

5. A water cooler comprising an upright elongated cabinet, a water cooling compartment and a food storage compartment in said cabinet, in vertical alignment and of substantially the same horizontal dimensions, insulation on said compartments, draft means on said water cooling compartment and an evaporator in thermal contact with both of said compartments.

10 In testimony whereof we hereto affix our
15 signatures.

JOHN A. MACREADY.
HARRY H. HODGSON.
